UNITED STATES PATENT OFFICE.

WILLIAM L. BRIDGEFORD, OF LOUISVILLE, KENTUCKY.

ADJUSTABLE BLOWER FOR STOVES.

SPECIFICATION forming part of Letters Patent No. 361,809, dated April 26, 1887.

Application filed June 1, 1886. Serial No. 203,696. (No model.)

To all whom it may concern:

Be it known that I, WILLIAM L. BRIDGEFORD, a citizen of the United States, residing at Louisville, in the county of Jefferson and State of Kentucky, have invented a certain new and useful Improvement in Adjustable Blowers for Stoves; and I do hereby declare that the following is a full, clear, and exact description of the construction and operation of the same, reference being had to the accompanying drawings, forming part of this specification.

This my invention relates to certain new and useful improvements in adjustable blowers for stoves in order to assist combustion, and also for the purpose of regulating the heat of the stove more perfectly, consisting more especially in a blower made in form to correspond with the front opening of the stove and kept in its place by means of slides on the jambs of the stove, in which it works loosely to permit of its being raised or lowered in regulating the draft, and is further provided with a catch hinged to the under side of the stove-top loosely, 25 with the hook on the inside, and a stationary catch secured to the upper edge of the blower, immediately under which an operating-handle is secured firmly to the blower, with lugs formed on the upper end, in which a small trigger is 30 hinged, which engages with the hinged catch on the stove above in rising, and thereby disengages it from the blower and permits it to be lowered or raised at pleasure, which is done by means of a small lifter, L, which slips over 35 the end of the handle.

The object of this my invention is to provide an adjustable blower for stoves that will be neat, cheap, durable, and more ornamental and convenient in use than the ordinary blowers now in common use.

I attain the above object by the mechanism illustrated in the drawings, in which—

Figure 1 is a perspective view of the stove, showing the blower and catch devices on the front. Fig. 2 is a sectional view of the blower 45 and part of the stove-front, showing the several catch devices thereon.

Similar letters refer to similar parts throughout the several views.

In the drawings, A represents the stove, 50 which may be made in any suitable form.

B is the fire-grate, and C is the fire-place opening.

D is the adjustable blower, which is made of metal and in form as shown in the drawings, with ornamental openings E E, filled with mica or other material.

F are the slides on the jambs of the stove, in which the blower D works up and down, and G is a small operating-handle secured to 60 the front of the blower, and H is a small trigger hinged in the upper part thereof for the purpose of disengaging the catch I from the stationary catch J on the blower when raised, which is done by means of a small lifter, which 65 takes hold of the handle G in raising the blower, and by means of the same lifter L the trigger H is raised, which disengages the catch I and permits the blower to be lowered, and by the same lifter it is raised again, and by means of 70 the automatic catches remains in position until lowered again. Therefore

What I claim as my invention, and desire to secure by Letters Patent in adjustable blowers for stoves, is—

The combination of the stationary front, the hinged catch I, the movable blower D, the catch J, trigger H, and hinged lifter L, substantially as described, and for the purpose set forth.

WILLIAM L. BRIDGEFORD.
